CAGELIKE ROTARY CLEANING BRUSH FOR THREADED BOLTS AND THE LIKE

Filed March 6, 1950

UNITED STATES PATENT OFFICE

2,600,338

CAGELIKE ROTARY CLEANING BRUSH FOR
THREADED BOLTS AND THE LIKE

James T. Starr, Brainerd, Minn.

Application March 6, 1950, Serial No. 147,790

1 Claim. (Cl. 15—179)

1

This invention relates to a rotary cleaner and more particularly a cleaning device operative by a portable power means in which different sized brush inserts are disposed from a rotatable shank for cleaning bolts, valve stems and like articles.

It is highly desirable that accumulation of scale and rust be removed from bolts before they are re-inserted in re-assembling automotive parts and like assemblies. This is particularly true of automotive cylinder head bolts or studs which are not usually removed from the block on removal of the cylinder head therefrom. These bolts are particularly susceptible to corrosion and when the head is slid back onto the bolts any accumulated scale thereon is likely to be scraped off onto the head gasket where it causes the development of "high spots" which will not allow the cylinder head to be uniformly tightened.

The "high spots" are not readily detected by the mechanic installing the head but if they are not detected and removed the usual result is water leakage and/or a "blown" head gasket. The cleaning of valve stems and other types of bolts presents similar problems and the cleaning methods used heretofore have not only proved costly and time consuming but do not always provide for certain removal of scale from screw threads and from under the head portion of a bolt.

According to the present invention I provide a rotatable cage-like frame in which a cleaning element is formed as an apertured disc having radially placed steel wire bristles having free ends directed inwardly to uniformly engage the shank and threads of a bolt or like article inserted therein.

It is among the objects of this invention to provide a portable cleaning tool for cleaning bolts and like articles.

Another object is to provide a rotary cleaner capable of accommodating relatively long articles.

Still another object is to provide a bolt cleaner having a radial brush formed with a ring of thread engaging bristles.

A further object is to provide a cleaning device having changeable inserts adapted to work articles of different diameters.

A still further object is to provide a cleaning tool for rotation by a portable drill or similar device as an assembly that is ready of manipulation, rugged, and economical of manufacture.

Other objects and purposes than those stated above consist in the arrangement, combination and details of construction disclosed in the drawing and specification, and then more particularly defined in the appended claim.

2

In the drawing in which like numerals refer to like parts:

Figure 1 is a top view of my invention taken on line 1—1 of Figure 2;

5 Figure 2 is an elevational view of the device partially sectionalized;

Figure 3 is a plan view with the bottom plate and brush removed; and

10 Figure 4 is an enlarged view of a section of the bolt thread being cleaned.

Referring now in detail to the drawing numeral 10 indicates generally the cleaning device of this invention. The device 10 is formed with a flat disc 11 having a centered aperture 12 of ample 15 diameter for insertion over bolts and like articles to be cleaned. The disc 11 is also formed of sufficient thickness to provide a downwardly opening recess 13 formed circumferentially around aperture 12. Recess 13 is dimensioned to receive in seated position therein of a circular brush 14 formed with a circular frame 15 of metal or like suitable material in which is mounted a plurality of radially positioned steel bristles 16. Each of the bristles 16 is provided with a free end spaced 20 equidistant from the axial center of the brush 14 to form a round receiving hole 17 centered relative to the brush. The receiving hole 17 is dimensioned to allow for insertion therethrough of the article to be cleaned with sufficient pressure being exerted thereagainst to scrape off any 25 dirt, scale, rust or like accumulation adhering to the article upon rotation of the brush. The proportioning of the receiving hole 17 is such that the bristles 16 are only slightly compressed so as not to cause them to fold back on themselves or 30 turn to the side of the article being cleaned. Such an article as the bolt 18 shown in Figure 2 being held by its head 19 between a pair of vise jaws 20 will be engaged along its entire shank surface as the brush 14 is moved downwardly 35 thereover during operation of the cleaning device 10 as hereinafter explained. The manner in which the bristles 16 are radially displaced is adapted to work their free ends deep into the valley 21 of a bolt thread 22 as best illustrated in 40 Figure 4. This arrangement of the bristles has the additional advantage that the knife-like cleaning surface presented by the bristles 16 allows for ready cleaning close under the head 19 or similar otherwise hard-to-get-at areas of bolts 45 and like articles to remove the scale, rust, etc. therefrom. A bolt so cleaned is restored to its original efficient holding capacity and is capable of being drawn to a tight, firm bolting position.

50 The brush 14 is held in its seated position in recess 13 by a circular bottom plate 23 center

apertured as at 24 so as to be alignable with disc 11. The bottom plate 23 is preferably of approximately the same thickness as disc 11 and is similarly recessed to form a recess shoulder 25 spaced from the top shoulder 26 of recess 13 formed in the disc. The matching recesses of the disc and plate are formed of sufficient depth to space shoulders 25 and 26 apart with the space therebetween being slightly less than the thickness of the brush 14 so that the brush will be held snugly in its seated position fixed against rotation relative to the disc 11 when the bottom plate 23 is tightened thereagainst by suitable screw bolts 26a or like holding means extending through suitable holes 29a in the disc and plate.

Extending upwardly from the disc 11 are a plurality of rods or arms 27 having secured ends 28 inserted in holes 29 spaced alternatively with holes 29a radially around the disc. The rods 27 are rigidly secured to the disc 11 by being welded thereto as at 30 as best shown in Figure 2 or by any other suitable holding means. Rods 27 are formed with parallel straight portions 27a of sufficient length to allow for insertion therebetween and through the disc 11 of the longest bolt or valve stem to be cleaned. Their radial arrangement and length provides a cage-like structure extending upwardly from the disc 11 under which is placed the brush 14 which not only provides an economical and efficient structure but also enables the user of the device to direct the brush to any spots or areas of the article being cleaned as found necessary. This structure and manner of operation allows for the rotation of a thin-edged brush over the exterior surface of a relatively long article to effect the uniform cleaning thereof. The straight portions 27a of the rods 27 merge into bent portions 31 disposed above the disc with the top ends 32 of the rods turned inwardly toward the axial center line of the device 10. The top ends 32 of the rods are in turn joined to a centered bar or shank portion 33 as by being welded thereto with the shank adapted for insertion in a drill chuck or like rotating means capable of supporting and rotating the device 10 about its axial center line. I have found that with this construction the device 10 operates very efficiently when inserted in a portable electric drill (not shown) and can be readily manipulated in close quarters at various locations about an automobile.

The operation of device 10 is very similar to that of drilling by means of a portable electric drill. First, a brush 14 of suitable size for the article to be cleaned is installed in the recess 13 with the bottom plate 23 bolted thereto by bolts 28. Selection of the right size of brush is a relatively routine matter as the receiving hole 17 of each brush 14 is dimensioned for working

standard size bolts and rods. Therefore, knowing the diameter of the article to be worked is all that is necessary to enable the user to select the right size of brush to be used. The shank 13 is then inserted in the drill chuck and the device 10 is then rotated at a relatively high speed. Whether or not the device 10 is to be lowered over the article to be cleaned or the article is to be inserted through the receiving hole 17 will depend primarily on whether or not the article is fixed or portable and ready of handling. In most instances it will be found that running of the rotating brush 14 several times over the length of the article to be cleaned will restore it to its original clean condition. However, in certain instances where the accumulation may be heavy the cleaning of the areas thereof can be readily observed through the open cage-like arrangement provided by rods 27 so that the other areas of the article need not be overcleaned.

Although the present invention has been shown and described in detail with certain combinations and relationships of parts, it will be appreciated that changes, alterations, modifications, and substitutions can be made without departing from the spirit and scope of the claim.

I claim:

A rotary cleaning device comprising a shank insertable in a drill chuck, a support means having legs extending from the shank with the ends thereof spaced radially from said shank, a flat disc carried by said legs and coaxially disposed with said shank for centered rotation therewith, an aperture formed in the disc for centered insertion therethrough of a round linear article to be cleaned, a flat circular brush carried by the disc for centered rotation therewith, said brush having inwardly directed radically disposed wire bristles all extending in approximately the same plane for circular engagement with the article being cleaned.
